UNITED STATES PATENT OFFICE.

ALPHA R. BEAL, OF NEWTON, MASSACHUSETTS.

EASEL.

SPECIFICATION forming part of Letters Patent No. 228,435, dated June 8, 1880.

Application filed October 17, 1879.

To all whom it may concern:

Be it known that I, ALPHA R. BEAL, of Newton, in the county of Middlesex and State of Massachusetts, have invented a new and useful Improvement in Easels, of which the following is a specification.

In all ordinary easels, whether with fixed or movable legs, so far as I know, no arrangement has been devised so that by spreading the legs the blackboard, picture, or other object may be grasped at both top and bottom.

My invention consists in the application of buttons, clamps, or other similar device, either fixed or movable, to the front legs of the easel, so that by spreading these legs the blackboard, picture, or other object is grasped, clamped, or held at both the top and bottom, and by closing the legs it is released.

Figure 1 in the accompanying drawings represents the front elevation of a three-legged easel opened and in use. A A' are the front legs; B, the rear leg. C C' and D D' are buttons or clamps, which grasp and support the frame E.

Fig. 2 represents a side elevation of the same;

B, the rear leg; A, one of the front legs; C and D, buttons or clamps attached to A, and E the frame.

The legs of the easel are so fastened together at the top that they may be closed or spread 30 apart, and the buttons or clamps are so arranged that by spreading the legs A A' the frame E is grasped or clamped at both the top and bottom.

Having described my invention, what I 35 claim, and desire to secure by Letters Patent, is—

The combination of the hinged front legs, A A', adapted to swing apart, with the upper clamps or equivalent devices, C C', and the 40 lower clamps or equivalent devices, D D', substantially as described.

In testimony whereof I have hereunto subscribed my name, in presence of two subscribing witnesses, on the 14th day of October, A. 45 D. 1879.

A. R. BEAL.

In presence of—

WARREN O. KYLE,
CHARLES F. HALL.
